UNITED STATES PATENT OFFICE.

JEWEL C. BLACK, OF ATHENS, ALABAMA.

CONTROLLING ATTACHMENT FOR CULTIVATORS.

Application filed June 7, 1924. Serial No. 718,604.

This invention relates to cultivator attachments, and particularly to an attachment peculiarly designed for use with walking or riding cultivators of certain types where-
5 in the beam of the cultivator is swiveled or mounted for lateral bodily movement.

One of the objects of the invention is to provide an attachment whereby the beam or the gang of cultivators may be set in just a
10 few seconds so as to run either to the right or left, that is so as to guide the gang or beam to the row or away from the row, whichever may be desired.

A further object is to provide means for
15 regulating the depth of plowing so that the cultivator may be set to plow either deep or shallow as may be desired.

A still further object is to provide an attachment of this character whereby the
20 gang or beam can be so set that it will be easy on the operator to guide when he wishes to, the attachment relieving the arms and shoulders of the operator from fatigue caused by holding the gang or beam.

25 Another object is to provide means whereby tension may be applied to large or heavy gangs or beams and less tension for light or medium gangs or beams so that when changing from heavy to light gangs the tension on the spring is changed at the time when the plows are changed, and that when changing from plows to scratchers less tension may be placed on the scratcher.

Still another object is to provide an attachment of this character which is very simple, may be readily applied to practically all makes of walking or riding cultivators or like machinery, and which will be thoroughly effective in practice.

40 My invention is illustrated in the accompanying drawings, wherein:-

Figure 1 is a plan view of a cultivator embodying a controlling attachment constructed in accordance with my invention;

45 Figure 2 is a vertical sectional view therethrough;

Figure 3 is an enlarged plan view of the attachment;

Figure 4 is a vertical sectional view
50 through the attachment;

Figure 5 is a section taken on the line
5-5 of Figure 4.

Referring to these drawings, it will be seen that my attachment is formed in two
55 main members or sections A and B. The

body A is formed of an integral casting, this casting being formed with an early circular barrel 10. This barrel extends nearly the entire length of the casting and at its rear end the barrel is longitudinally spilt 60 or slotted, as at 11, the rear end of this slot being defined by the two upwardly extending ears 12. Below the barrel the body A is formed to provide a vertical web 13 whose lower wall is upwardly curved or concave. 65 The rear end of this vertical web 13 terminates in a transversely extending abutment 14 apertured, as at 15, and the ends of the abutment are connected to the barrel by means of vertical flanges 16. The forward 70 end of the barrel is transversely slotted, as at 17. Extending upward from the forward end of the barrel is a bracket 18 which, at its upper end is angularly extended forward, as at 19, and formed with a nut receiving bore 20, this nut receiving bore being internally screw-threaded. The wall of the bore 20 is split and this split is defined by the two ears 21 which are apertured for the passage of a bolt 22. 75

The lower end of the casting A is extended forward to provide a supporting arm 23 and this supporting arm is formed with a downwardly conical socket 24. The portion 19 is T-shaped in cross section, as illustrated 80 in Figure 3, to provide a transversely extending abutment portion 25 whose upper face is inclined downward and rearward, as shown in Figure 4. The web 18 is connected with the side walls of the barrel by 90 means of a transverse web 26. A bolt 27 passes through the ears 12, this bolt acting to clamp the barrel onto a cultivator beam C, as shown in Figure 3.

The second main section or member of the 95 attachment comprises a casting, designated generally B, as before stated. This casting is so formed as to provide two longitudinally extending arms 28, these arms being connected at their forward ends by a transverse 100 bar 29 so that the arms, together with this bar, constitute a yoke. The forward ends of the arms are slightly inclined downward but extend approximately in a horizontal plane, but towards the rear the arms extend 105 downward and rearward and slightly forward, as at 30, terminating in eyes 31 which are adapted to be disposed on each side of the abutment 14. The two arms 28 are connected by a transverse cross bar 32 which 110

is screw-threaded for the passage of an adjusting screw 33, which at its lower end bears against the abutment or cross bar 25 so that by turning this screw 33 inward, the 5 arms may be raised relative to the casting A, the arms pivoting upon the bolt 34 which passes through the eyes 31 and through the aperture 15 formed in the abutment 14. The arms 28 extend forward considerably beyond 10 the eye 18 and on each side of the screw-threaded bore 20, and, as before remarked, the forward ends of the arms are connected by a transverse cross bar 29 which is slightly curved or bowed forwardly, the inner face 15 of this cross bar being formed with a plurality of notches 35, as seen in Figure 3.

Also coacting with the members or sections A and B is an approximately U-shaped brace, which consists of two rearwardly 20 divergent, forwardly connected arms 36 and 37. The arm 36 is longer than the arm 37 and at its rear end terminates in a head 38 which is formed with a semi-circular seat or recess 39 adapted to receive the head 40 of a 25 bolt 41, which in turn is adapted to pass around one of the frame bars of the machine. The arm 37 is divergently extended with relation to the arm 36 and at its end is formed with a rectangular head 42 having 30 a central aperture 43 for the passage of a bolt. The middle of this V-shaped brace 37 is formed with an outwardly extending portion 44 having a plurality of notches 45 which extend in a fore and aft series, and 35 adapted to engage with these notches is the angularly bent end 46 of a coiled contractile spring 47, the other end of this spring being rearwardly extended and formed with an angularly extended end 48 which is adapted 40 to engage in any one of the notches 35.

In Figure 1, I have shown so much of a 45 cultivator as is necessary to illustrate my device, and it will be seen that the cultivator which I have shown is of that type wherein the beams are connected to the arched axle of the cultivator by means which will permit the beam to swing vertically or horizontally, the beams carrying handles whereby the beams may be manipulated and 50 shifted nearer to or further from each other. I have illustrated a walking cultivator, but it will be understood that my device might be applied to a riding cultivator and to a large variety of different types of cultivators. In the form of cultivator shown, the 55 arched axle is designated D'. This arched axle has a downwardly extending leg E which extends laterally, as at F, and then rearwardly at G and then outward, as at H, providing for the support of the wheels I. The cultivator beam C carries the ordinary 60 cultivator shovels J, and it will be understood, of course, that any cultivating implements might be mounted upon the beams. 65 These beams are circular in cross section in

the form of cultivator for which I have particularly designed this attachment, and I have illustrated such beams, though I do not wish to be limited thereto.

The means for raising or lowering the 70 cultivator beams, adjusting the cultivator shovels, and the particular mounting of the tongue K form no part of my invention and, therefore, I have not attempted to illustrate these parts in detail. The beam C, as shown 75 in Figure 2, is disposed within the barrel 10 and is held in place by being clamped within the barrel by means of the clamp bolt 27 passing through the ears 12, and is also held in place by the bolt passing through the 80 slots 17. It will be understood that the beam C may be rotated axially within the barrel into any desired adjusted position and either toward the right or toward the left. The casting A, it will be seen, is to a certain extent like the knuckle which is used to 85 swivelly connect the beams to the arched axle of the ordinary cultivator of this type. To this end, a spindle L is disposed between a nut M mounted in the opening 20 and the 90 lower end of the spindle being somewhat conical in form and seated within the socket 24. The upper end of the spindle is formed with a central pin l which extends through the center of the nut M so that the nut, when 95 turned down, will bear against the upper end of the spindle. Loosely surrounding the spindle and rotatable thereon is a sleeve or collar N having a forwardly extending arm n, this arm terminating in a sleeve O 100 which is adapted to fit around and rotate upon the portion F of the axle. So far as I have described, the element A is very much the same as the kindred element found in 105 cultivators of this type, except that the element A as I have described it is provided with a cross bar or abutment 25 against which the screw 33 bears, for a purpose as will be later stated.

It will be seen that the element B, which 110 is particularly the novel element of the attachment which I have produced, is pivotally mounted upon the element A below the line of draft for the beam and that it arches up so that the forward end of the 115 yoke of element A is above the line of draft. It is to be particularly noted that the point of pivotal connection of the yoke B to the element A is, as before remarked, below the line of draft and on a level below 120 the pivotal point for the beam C and that the point of connection, as shown in Figure 2, of the spring 47 with the yoke is such that the pull of the spring 47 is upward on the lower end of the yoke and that this being below the line of draft, the pull on 125 the beam C is downward and thus the gang will be pulled into the earth, while the set screw 33 of the yoke or lever B will regulate the depth of cultivation, and the action 130

of this set screw 33 is to depress or raise the forward end of the yoke B, thus regulating the downward pull on the beam C and thus in a way either forcing the beam C upward 5 or permitting it to move downward. It is further to be noted that a line connecting the brace 29 at the forward end and the pivot 34 at the rear end of the yoke B is at a very acute angle to the direction of the 10 beam C, the rear end of the yoke being pivoted at 34 four or five inches below the horizontal center of the beam C. This makes such a balance of the parts that the beam can be operated with perfect ease and 15 the gangs will run along where the row is straight any depth at which it is desired to cultivate.

With my construction, when it is desired 20 to change the tension of the spring 47, it can be changed to any extent by simply raising the rear end of each beam to an upright position, which is assisted, after once the line between the rear end of the spring 47 and the pivot 34 has passed above the 25 axle H, by the spring 47, then readjust the forward end of the spring in any one of the seats 45, thus increasing or decreasing the tension of the spring and then lowering the beam again to its working position.

20 With my construction, in actual practice just six seconds are required to adjust the tension of the spring. Furthermore, with my construction the beams can be raised to an upright position and the operator thus 25 has plenty of room to change the blades or remove the blades for resharpening. He can stand while removing the blades J or adjusting them and be in the best possible position for work and without any necessity of kneeling down on the ground or stooping over in order to remove the blades. The forward end of the V-shaped brace is disposed about on a level with the uppermost portion of the yoke B and the spring, 40 therefore, exerts an upward and forward tension upon this yoke B. Inasmuch as the brace D is bolted rigidly to the two parts of the frame, it follows that the spring 47 will draw the yoke B slightly upward 45 and that the further along the hook 46 of the spring is adjusted in the recesses 45, the greater will be the tension on the spring. Furthermore, as shown in Figure 1, assuming 50 that the attachment is disposed, for instance, on the right hand side of the cultivator, it will be obvious that if the spring be adjusted to one of the notches 35 in the extreme left hand side of the yoke 28, the 55 spring will tend to pull the plow beam inward, or in other words will guide the gang or beam to the row, whereas if the hook 48 be engaged with the recess 35 on the extreme right hand side of the yoke 28, it will be 60 obvious that the gang or beam will be guided away from the row and if the spring, on the

other hand, is disposed parallel to the line of draft, it will be obvious that the plow will be guided straight.

It will be seen that this device will set the 70 gang or beam so as to make it very easy on the operator to guide the plow. It will relieve tired arms and shoulders and other fatigue caused from holding the gang or beam, and the gang or beam will run and guide with 75 ease with this attachment and not tire the operator. The notches 45 permit the tension of the spring to be taken up from time to time, with the greatest tension for large or heavy gangs or beams and less tension for light or medium gangs or beams. Thus 80 when changing from a heavy to a light gang, it is an easy matter to simply change the tension on the spring, and furthermore when changing from cultivator plows to mere scratchers, the scratcher being lighter 85 requires less tension on the spring and, of course, the tension is released by setting the hook 46 in the rearmost notch. If it be desired to pull the scratcher into the ground, then by manipulating the adjusting 90 screw 33 and adjusting the spring in the notches 35 and 45 the gang or beam may be made to stay in the ground or pulled into the ground for any depth desired.

The adjusting screw 1 is for regulating 95 the depth of plowing and by this means the attachment may be set to cause either deep or shallow plowing. Thus when the screw 33 is turned downward, it will tend to raise 100 the rear end of the plow beam, the plow swinging on the pivot formed by the collar. Of course, this depression of the screw 33 tends to move the yoke partly upward. The spring 47, however, does not resist this upward movement. Whenever the screw 33 105 has been turned so as to cause the beam to pass the center line or normal line of draft, the plow will be pulled into the ground and, on the other hand, when raising the plow out of the ground the tension of the 110 spring 47 will act to assist in lifting the plow, after the pivot 34 has passed the center upon which the member A operates, and help to put it in the rack, that is in 115 a suspended position. It will be understood that by changing slightly the proportions and form of the V-shaped brace formed of the parts 36 and 37 and changing the cross section of the barrel 10, this device can be 120 used on any type of cultivator as well as on the particular type which is illustrated in the drawings.

I claim:—

1. The combination with a cultivator having 125 a frame and a beam mounted upon said frame for pivotal movement in a vertical plane and pivotal movement in a horizontal plane, of a yoke operatively pivoted to the beam rearward of the pivotal axes of the beam for both vertical and horizontal move-

- ment and below the pivotal axis for vertical movement, the yoke extending upward and over the beam and bearing upon the same rearward of both the pivotal axes and then 5 extending forward in advance of both pivotal axes, and a spring operatively connected at its forward end to the frame of the machine and at its rear end connected to said yoke, the spring exerting tension on a 10 line below the axis of vertical movement for said beam to thereby urge the rear end of the beam downward and yieldingly resisting oscillation of the beam and of the yoke upon the horizontal axis of the beam.
- 15 2. The combination with a cultivator having an axle and wheels mounted thereon, of a beam operatively connected to the axle on a horizontal axis for swinging movement in a vertical plane, a yoke pivotally connected at its rear end to the beam at a 20 point on a level below the horizontal axis on which the beam swings vertically, said yoke midway of its ends bearing upon the beam, a spring operatively supported by the 25 axle in advance of said yoke, said spring at its rear end having engagement with the forward end of the yoke and exerting tension on a line extending between the forward and rear ends of the yoke and below the 30 said pivotal axis of the beam whereby said spring acts to yieldingly depress the beam.
- 35 3. The combination with a cultivator having an arched axle and wheels supporting said axle, a tongue attached thereto and a beam extending rearward from the axle, of a 40 member mounted upon the forward end of the beam and operatively connected to said axle for swinging movement in horizontal and vertical planes, an arched yoke pivotally connected at its rear end to said member at a point below 45 the pivotal axis of the beam for vertical movement and embracing said member and extending upward and forward beyond the pivotal centers of the same and operatively bearing against the beam, means mounted on the yoke for adjustably bearing against the upper face of said member, and a tension spring operatively supported upon the frame of the machine and engaging the 50 forward end of the yoke and yieldingly holding the forward end of the yoke in a predetermined position, the forward and rear ends of the yoke being disposed on a line 55 extending below the axis on which the beam swings vertically whereby to cause the spring to exert a downward pressure on the rear end of the beam.
- 60 4. The combination with a cultivator having an arched axle, wheels supporting said axle, a tongue attached thereto and a beam extending rearward from the axle, of a member mounted upon the forward end of the beam and operatively connected to said axle for swinging movement in horizontal and vertical planes, an arched yoke pivotally

connected at its rear end to said member at a point below the level of the pivotal axis of the beam on which it swings for vertical movement, said yoke embracing the member and extending upward and forward beyond 70 said last named pivotal center of the member, means mounted on the yoke for adjustably bearing against the upper face of said member, a tension spring operatively supported upon the frame of the cultivator and 75 engaging the forward end of the yoke and yieldingly holding the forward end of this yoke in a predetermined position and against lateral movement, the yoke including a transversely extending bar at its forward 80 end and the spring being engageable at any one of a plurality of points along said bar to thereby exert tension on the yoke and urge the beam in a plurality of positions relative to the line of draft, the ends of the yoke 85 being disposed on a line below that pivotal axis of the beam upon which the beam swings in its vertical movement.

5. The combination with a cultivator having a frame, an arched axle, wheels supporting said axle and a tongue operatively connected to the frame, a beam extending rearward from the axle, of a member mounted upon the forward end of the beam and operatively pivoted to the axle for swinging movement in a horizontal and a vertical plane, an arched yoke pivotally connected at its rear end to said member at a point below and rearward of the axis upon which said member and beam swing in a vertical plane, 90 said yoke embracing the member and extending upward and forward beyond said last named pivotal axis thereof, means mounted on the yoke for adjustably bearing against the upper face of said member, a brace operatively bearing against and connected to the axle and extending forward therefrom, and a tension spring operatively connected at its forward end to said brace and at its rear end engaged with the forward end of the yoke, the forward and rear ends of the yoke being disposed on a line passing below that axis of the member upon which the member and beam vertically swing. 105

6. The combination with a cultivator having an arch including a medially disposed vertical portion and a horizontal portion outward of the vertical portion, a wheel carried by said horizontal portion, the cultivator having a beam engaging the arch outward of the vertical portion for pivotal movement in a horizontal and vertical plane, of a yoke operatively pivoted to the beam rearward of and below the horizontal pivotal axis of the beam, the yoke extending over and bearing upon the beam and extending forward beyond the horizontal pivotal axis of the beam, the forward and rear ends of the yoke being disposed in a plane 110

extending below the said pivotal axis of the beam, an approximately V-shaped brace projecting forwardly from the arch and engaging the latter for adjustment in a vertical plane, and a spring having its forward end engaged with said brace and its rear end engaged with the forward end of the yoke, said spring normally exerting tension upon the yoke on a line below the said pivotal axis of the beam.

7. The combination with a cultivator having a frame including a medially disposed vertical portion and a horizontal portion outward of the vertical portion, a wheel carried upon the horizontal portion of the frame, a beam engaging the arch outward of the vertical portion for pivotal movement in a horizontal and a vertical plane, of a yoke operatively pivoted to the beam rearward of and below the horizontal pivotal axis of the beam, the yoke extending over and bearing upon the beam and extending forward beyond the said pivotal axis of the beam, a spring having its rear end connected to the forward end of the yoke and normally exerting tension upon the yoke on a line below the said pivotal axis of the beam, and means for supporting the forward end of the spring upon the frame of the cultivator, said means being vertically adjustable.

8. The combination with a cultivator having an arched axle and wheels supporting said axle, of a beam operatively connected to the axle for swinging movement in a vertical and a horizontal plane, a two-armed yoke embracing the forward end of the beam

and extending downward below the same and pivotally connected at its lower end operatively to the beam on a level below the horizontal pivotal axis of the beam, means acting to yieldingly draw the forward end of the yoke forward, the forward and rear ends of the yoke being disposed on a line below the horizontal pivotal axis of the beam and an adjusting screw passing through the yoke and operatively bearing against the beam rearward of the pivot for its vertical swinging movement.

9. The combination with a cultivator having an arched axle and wheels supporting said axle, of a beam operatively connected to the axle for swinging movement in a vertical and a horizontal plane, a two-armed yoke embracing the forward end of the beam and extending downward below the same and pivotally connected at its lower end operatively to the beam at a point below the level of the horizontal pivotal axis for the beam, a V-shaped brace attached to the arched axle of the cultivator and projecting forward therefrom, and a coiled contractile spring engaged with the forward end of said brace and at its rear end engaged with said yoke, there being means whereby the tension of the spring may be adjusted, the forward and rear ends of the yoke being disposed on a line below the horizontal pivotal axis of the beam.

In testimony whereof I hereunto affix my signature.

JEWEL C. BLACK.
